(57) **CLAIM**

The ornamental design for the rail planter, as shown and described.

DESCRIPTION

This application is related to Design patent application Ser. Nos. 29/571,930 and 29/571,932, both filed concurrently herewith.

FIG. 1 is a perspective view showing a rail planter in accordance with a new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the rail planter that form no part of the claim.
